UNITED STATES PATENT OFFICE

ANTONIO S. ROMERO, OF SANTURCE, PORTO RICO

FOUNTAIN PEN

Application filed January 8, 1927. Serial No. 159,835.

The present invention relates to penholders and more particularly to that class known as fountain pens, wherein a reservoir for holding writing fluid is provided in combination with self-contained means for filling the reservoir. The invention aims to provide numerous new and useful improvements in construction and operation hereinafter more specifically described and pointed out in the appended claims.

The invention will best be understood from a description of one selected embodiment thereof illustrated in the accompanying drawings, to which reference may be had.

Referring to the drawings, Fig. 1 represents a side elevation of the device assembled in the closed position;

Fig. 2, a longitudinal section of the cap on an enlarged scale, the same being shown in detached position preparatory to mounting on the butt end of the pen for filling purposes, a portion of the latter being also illustrated;

Fig. 3, a side elevation of the device shown on an enlarged scale and partly in section, the cap being operatively mounted on the butt end of the pen for the filling operation;

Fig. 4, a sectional view on the line 4—4 of Fig. 2, showing interior details of the plunger structure; and

Fig. 5, a rear end view of the pen.

The penholder comprises a hollow stock or barrel 1 having a removable front portion fitted with a pen 2 and feeding finger 3 and provided with a longitudinally arranged fluid duct 4 communicating with the interior of the barrel. Mounted on the front end of the penholder and enclosing the pen 2 when not in use is a cap 5, detachably secured thereto by the engagement of a threaded portion 6 exteriorly provided on the penholder by a threaded portion 7, interiorly provided on the cap. When it is desired to use the device the cap 5 is removed and preferably mounted on the butt end of the penholder, being secured thereto by the engagement of the threaded portion 8 exteriorly provided on the butt by the threaded portion 29 of a movable sleeve member or plunger 17 carried within the cap and hereinafter more particularly described.

When it becomes necessary to refill the barrel 1 with writing fluid this may be accomplished by means of the cap 5 which is designed to co-operate with the penholder in the manner hereinafter described whereby suction is applied to the butt end of the penholder to evacuate air from the barrel to permit a corresponding amount of writing fluid from a source of supply to enter the barrel through the duct 4 while the front end of the pen is immersed in the fluid supply. As the chamber within the barrel is normally entirely free of all obstructions or solid matter, such for example as valves and ducts commonly present in self-filling fountain pens, its capacity is limited solely by its size undiminished by the presence of solid bodies and hence is commensurate with and exactly equal to the maximum internal volume of the chamber.

The butt end of the penholder is formed with a reduced extension portion 9 exteriorly threaded with a left-hand thread which is engaged by an adjustable cap 10 interiorly provided with a corresponding thread. The extension portion 9 is hollow and closed by an end wall 11 having a vent 12 therein. Said vent 12 is permanently open and arranged off center. The cap 10 is also provided in its end wall with a vent 13. When the cap 10 is in a retracted position these vents afford passages for the escape of air from the barrel 1, but when the cap is screwed down to the limit of movement the engagement of the end walls of these parts seals the vents, as in this position the vents are arranged out of registering position.

The cap 5 is provided with a removable cover 14 normally arranged as shown in Fig. 1, and secured thereon by an exteriorly provided screw thread 15 which is engaged by a corresponding thread 16 interiorly provided on the cover. The cover 14 is employed in the normal position to hold in stationary position within and at the outer extremity of the cap 5 the movable sleeve member or plunger 17 before referred to, said plunger being adapted to slidably engage the inner wall of the cap 5. Detachable connection between the cover 14 and plunger 17 may be effected

in any suitable manner, herein exemplified by the provision of a leaf spring 18 which is crowned lengthwise and diametrically arranged within the cover with its ends extending away from the end wall of the cover. Said spring is rigidly secured at its middle to the cap by a hollow rivet 19 and extends at opposite ends into marginally communicative T slots 20 provided in this end of the plunger, a slight turning movement of the cover after said ends of the spring have penetrated said openings being sufficient to lock the parts together in tensional engagement.

When applying the cap 5 for the refilling operation, the cover 14 is first removed from its normal position and placed on the opposite end of the cap, which is also exteriorly provided with a suitable thread 21 for the purpose. The plunger 17 is now released and free to be moved to the opposite end of the cap which is done by inserting the butt end of the penholder. The plunger is provided at opposite points on the margin of its inner end with notches 22 which enable it to straddle the spring 18 when advanced to the limit of upward movement and to prevent turning of the plunger while connection between the penholder and plunger is being established. This is done by extending the butt end of the penholder, including the cap 10, into the interior of the plunger and then rotating the former whereby the thread 8 is induced to engage a corresponding thread 23 interiorly provided on the plunger as shown in Fig. 3. In performing this operation suitable means are provided for simultaneously releasing the cap 10 thereby opening the vents 12 and 13, said means being exemplified herein by the provision of longitudinal keys 24 arranged at opposite points centrally interiorly of the plunger which are adapted to fit into corresponding grooves 25 provided exteriorly on the cap 10. Hence, as the penholder is rotated to establish connection with the plunger, the latter is held against rotation by engagement of the notches 22 with the spring 18 while at the same time the cap 10 remains stationary by reason of the engagement of the grooves 25 by the keys 24. As the thread securing the cap 10 is formed in a direction opposite to that of the thread 23 on the plunger the turning of the penholder to the right involves a release of the butt end from the cap 10 which is moved relatively thereto in a longitudinal direction. The cap 10 is interiorly threaded throughout its length which is made sufficient as shown in Fig. 3 to avoid complete separation from the penholder at all times during rotation of the latter within the plunger.

To refill the barrel 1 the pen 2 is preferably wholly immersed in the writing fluid at the source of supply and while in this position the cap 5 carrying the plunger 17 is retracted, care being taken by the operator at the same

time to place a finger over the vent 30 in the rivet 19 in the center of the cap 10, the upstroke of the plunger being adapted to evacuate air from the barrel through the vents at the top, thereby creating a vacuum which is filled by the fluid entering at the opposite end through the duct 4. To avoid separation of the plunger from the cap 5 during retraction of the latter, a suitable stop may be provided, herein shown in the form of an expansible ring 26, seated in an annular recess of corresponding proportions provided in the outer wall of the plunger at a point preferably near the top, said ring being adapted to expand upon entering an annular recess 27 of graduated depth provided on the inner wall of the cap 5 at a point near its lower extremity, whereby the cap at the bottom of said recess presents a shoulder which is engaged by the ring. Said ring is preferably slightly beveled on the lower margin of its exposed surface as at 28 to prevent stripping of the threads 7 on the inner wall of the cap.

It is desirable, although not essential, to construct the barrel 1 in whole or in part of transparent or translucent material to aid the operator in detecting the level of the writing fluid as it rises within the barrel during the filling operation, to prevent overcharging. When a sufficient quantity of the fluid is obtained in this manner the penholder is reversely rotated to again seat the cap 10 to close the air vents, separation of the plunger 17 and cap 5 from the penholder being thereby simultaneously effected. When this has been accomplished the cover 14 of the cap 5 may be restored to its normal position on the opposite end of the cap and the plunger again secured thereto in the manner before described.

It will be understood that I do not intend to limit my invention to the particular embodiment herein shown and described, but the invention is intended to cover all such modifications of said embodiment as come within the scope of the appended claims.

I claim as my invention:

1. A fountain pen comprising, in combination with a penholder having a reservoir to contain writing fluid, a cap portion for application to either end of the penholder, and a plunger member mounted in and normally carried by the cap portion for detachable connection with the butt end of the penholder for filling said reservoir.

2. A device of the class described comprising, in combination, a barrel having oppositely arranged passages communicating with its interior, a cap closed at one end and adapted to be mounted on either end of the barrel, and a plunger mounted in and normally carried by the cap for detachable connection with the butt end of the barrel for filling the barrel.

3. A fountain pen, comprising, in combination, a barrel portion closed at opposite

ends, each of said ends having a passage therethrough, means for opening and closing one of such passages, a cap portion for detachable engagement with either end of the barrel portion, and a sleeve within the cap adapted to be detachably applied to the butt end of the barrel portion, said cap and sleeve being cooperatively associated to operate as a pump for withdrawing air from the barrel.

4. A device of the class described comprising, in combination, a penholder having a closed chamber and an opening at one end communicating with the chamber and a separate closable opening at the opposite end communicating with the chamber, a removable cap adapted to be applied to and to fit over either end of the penholder, and a member slidably mounted within the cap and adapted to be detachably associated with the penholder to operate as a plunger for evacuating air from said chamber.

5. In a self-filling fountain pen, in combination with a penholder having a reservoir to contain writing fluid and separate passages communicating with the reservoir at opposite ends of the penholder, a cap adapted to be fitted over either end of the penholder and comprising a tubular portion, a detachable member for sealing one end of the tubular portion, and a sleeve within the tubular portion adapted to be detachably secured to the rear end of the penholder for the support of the tubular portion and operable therewith to evacuate air from said reservoir.

6. In a device of the class described, in combination with a penholder having a reservoir to contain writing fluid and separate passages communicating with the reservoir at opposite ends of the penholder, adjustable control means on the butt end of the penholder for opening and closing the corresponding passage to the reservoir, a reversible cap adapted for engagement with either end of the penholder, and means carried in the cap for cooperative association with the cap and the penholder for filling said reservoir with said fluid, said filling means in said cap being adapted to operate said passage-control-means during engagement of said cap with the penholder.

7. A fountain pen comprising, in combination, a penholder having a reservoir to contain writing fluid, said reservoir having an inlet and an outlet, an adjustable valve member for controlling said outlet, a cap for application to either end of the penholder, and a plunger mounted in and carried by the cap for cooperative association with the cap and the penholder for filling said reservoir, said plunger being adapted to coact with said valve member to open and close said outlet.

8. A device of the class described, comprising, in combination, a penholder having a reservoir to contain writing fluid, a cap for application to either end of the penholder,

a plunger member mounted in and carried by the cap for detachable connection with the penholder for filling said reservoir, and a stop for limiting the outward movements of the plunger member.

9. A fountain pen comprising, in combination, a barrel having a chamber to contain writing fluid with a fluid-receiving capacity commensurate with its maximum internal volume, and self-filling means normally mounted on and carried by the barrel and including a plunger having threaded engagement with the barrel during the filling operation.

In testimony whereof, I have signed my name to this specification.

ANTONIO S. ROMERO.
